UNITED STATES PATENT OFFICE.

KARL WAHL AND JOHANN RIXY, OF PRAGUE, AUSTRIA-HUNGARY.

BUILDING PLATE OR TILE.

SPECIFICATION forming part of Letters Patent No. 552,939, dated January 14, 1896.

Application filed June 13, 1895. Serial No. 552,698. (No model.)

To all whom it may concern:

Be it known that we, KARL WAHL and JOHANN RIXY, subjects of the Emperor of Austria-Hungary, residing at Prague-Smichew, Bohemia, Empire of Austria-Hungary, have invented certain new and useful Improvements in Building Plates or Tiles, of which the following is a specification.

The object of the present invention is a plate made of clay, plaster-of-paris, cement, terra-cotta, or similar material, which is especially appropriate for blending the fronts and walls of buildings. It may be also decorated on its outside surface, so as to be used for making cornices, stucco-work, &c. This new plate is shown in the accompanying drawings, in which—

Figure 1 is a perspective view of a plate for fronts. Fig. 2 is a perspective view of a plate intended for blending smooth walls. Fig. 3 is an under side view of the plate, Fig. 1. Fig. 4 shows several plates united for front walls. Fig. 5 shows several plates united for other walls. Fig. 6 is a cross-section on line $x x$, Fig. 4.

The inside A and the outside B of the plate are of the same size, but they are shifted against each other in such a way that offsets a and b are formed. By this shifting of the outer surfaces against each other we obtain in the simplest way that the joints of the upper and lower faces are not below each other, but, on the contrary, come considerably apart, and that the passing of moisture is thus absolutely prevented, as the individual plates overlap, when the blending of a wall is effected, Fig. 6.

The insides of the plates are provided with grooves c to increase the adhesion of the cement or mortar and to produce a better binding on the walls. Besides these grooves c longitudinal and cross grooves d and e are provided on the inside of the plates, so that in case of need the plates can easily be separated in halves, quarters, and eighths. These grooves on the inside are therefore so disposed on the plate that the outside surface can be divided in halves, &c., as stated. In order to enable the workman to cover also wooden walls or frame houses with these plates, holes f are provided, through which screws can be passed.

A groove g is provided for the object to receive a wire, in order to effect a solid combination of the plates.

55

It is a great advantage of the plates for front walls that the placing upon the walls in accurate distances can be effected very easily and quickly when bars h are made to project from the surfaces of the offsets a and b . 60 These bars are so placed upon the offset b that the plates, when secured side by side, abut with their edges i against said bars, and that then the joints at the vertical edges fall exactly in the middle below the outside surface of the adjacent plate above. Thus quick work is possible to cover a wall, and also the greatest accuracy in the work is obtainable, whereby the outer appearance of a wall lined with these plates is highly improved.

70

These plates may also be employed for covering walls inside of buildings, kitchens, bathrooms, halls, &c., where, by dispensing with the bar h , the plates close completely together with their edges. This is of special advantage 75 for walls inside of buildings which are damp, for the plates form with their closed joints an impermeable lining, as each joint is covered by the overlap of the adjoining plate, so that the passage of moisture and also the displacement of the plates are utterly impossible. This advantage cannot be obtained with the ordinary plates now in use.

80

These plates, as already stated, can also be employed with best advantage in frame 85 houses, where the ordinary plates could not be used. In this case the plates are secured on the wall by means of screws and the joints are filled with cement or plaster. By this means the wall obtains an appearance equal 90 to that of brickwork covered with mortar, and houses can be cheaply erected in elegant and durable style.

The output of cost for a frame house with these plates being about half the cost only of 95 a brick building shows how great an advantage is offered by these plates over the ordinary plates of known style.

Buildings erected with these plates admit also of a very effective ventilation of the walls 100 and are fireproof in every respect.

The plates may be used also directly as material to erect walls and offer the same advantages as walls of stone, brick, and other ma-

terial. The cost, however, is much less than ordinary brick walls.

We claim as our invention—

1. Facing plates of plaster, clay, cement, terra-cotta or similar material with inside and outside surfaces A, B of equal size, being shifted against each other and forming offsets *a b* so as to overlap the joints, to prevent the passage of moisture and to prevent the displacement of the individual plates, and having the spacing bars *h*, substantially as described.

2. Facing plates of plaster, clay, cement, terra-cotta or similar material with inside and outside surfaces A, B of equal size, being shifted against each other and forming offsets *a b* so as to overlap the joints, provided with

grooves *g* for wires and holes *f* in line with said grooves, as described.

3. Facing plates of plaster, cement, clay, terra-cotta or similar material with inside and outside surfaces A, B of equal size, being shifted against each other and forming offsets *a b* so as to overlap the joints, provided with grooves *d e*, provided with grooves *g* and screw holes *f* and provided with bars *h* substantially as and for the purposes set forth.

In witness whereof we have hereunto set our hands in presence of two witnesses.

KARL WAHL.

JOHANN RIXY.
